UNITED STATES PATENT OFFICE.

JOSEPH EIFEL, OF CHICAGO, ILLINOIS.

LOOSE-LEAF HOLDER.

1,167,639.

Specification of Letters Patent.

Patented Jan. 11, 1916.

Application filed November 17, 1911. Serial No. 660,821.

To all whom it may concern:

Be it known that I, JOSEPH EIFEL, a citizen of the United States, and a resident of Chicago, in the State of Illinois, have invented certain new and useful Improvements 5 in Loose-Leaf Holders, of which the following is a specification.

My present invention relates in general to devices for fastening together loose sheets 10 of paper, and more particularly to devices for fastening such sheets in a file cover or folder, and has special reference to the provision of an improved, inexpensive and compact form of device.

15 The principal objects of my invention are the provision of a device of the character referred to which may be readily formed of very thin material to the end that when it is applied to a folder, the increase in the thickness 20 of the folder consequent upon such application and therefore the amount of space such folder occupies in a filing case will be minimized as far as may be; the provision of a holder device which will permit of 25 practically instantaneous separation and replacement of the relatively movable parts when adding or moving sheets therefrom; to accommodate the additional sheets from time to time inserted therein; the provision 30 of a device adapted for the ready removal of parts of the number of sheets held thereby without any disturbance of the remainder of such sheets; the provision in a holding device of a plurality of engaging 35 members so oppositely arranged on a continuous base as to most readily coöperate upon being caused to approach; the provision in a file cover of a ball and socket device for retaining sheets therein upon pressure 40 exerted exteriorly of such cover, together with such further and additional objects as may hereinafter appear.

45 Loose sheet and file covers and fastening devices in use at this day, as known to me, are largely objectionable in one of the two following principal respects, viz.: either they lack positively acting means for retaining the sheets therein, or, if provided with such means, are of such great bulk that they cannot 50 be economically used, and especially are not available for use in covers normally holding but relatively few sheets, on account of the large amount of waste space involved in their use.

55 In attaining the objects above set forth, together with certain advantages to be be-

low disclosed, and in overcoming the disadvantages and objectionable features mentioned, I have provided the construction illustrated on an enlarged scale in the accompanying drawing, wherein—

Figure 1 is a sectional view of a file cover embodying my invention; Fig. 2 is a plan view of the ball element of Fig. 1; Figs. 3 and 4 are views, similar to those of Figs. 1 and 2, illustrative of another embodiment of my invention and of the socket element; Fig. 5 is an elevational view of the ball device of Fig. 3. Figs. 6 and 7 are respectively elevational and plan views of a combined ball-and-socket retaining and lengthening member, Fig. 7 being partly in section taken on the line VII—VII of Fig. 6; Fig. 8 is an elevational view of a modified form of lengthener; Fig. 9 is an elevational view of another form of retaining member; Fig. 10 is a plan view of another form of the socket element; Figs. 11 and 12 are plan views of two forms of the ball and socket device mounted on a unitary base; Fig. 13 is an edge view of the device of Fig. 12; and Fig. 14 is a view illustrative of the device of Figs. 12 and 13 applied to a file cover with the devices of Figs. 6 and 8 interposed in operative positions therein.

55 The file cover may be of paste-board, cloth or paper of a suitable weight, and the engaging devices should be formed of material as thin as it is feasible to employ, preferably somewhat stiff in order that it may retain the form given it, and desirably possessed of a certain amount of resiliency or springiness for reasons which will shortly appear.

90 Referring first more particularly to Fig. 1, it will be noted that in the embodiment of my invention here illustrated, where I have shown my improved loose sheet holder in combination with a folder or file cover 10, I employ, for the purpose of retaining the loose sheets in the cover, a suitable number of interlocking fastening devices, preferably ball and socket members, 11 and 12. For the purpose of fastening the ball member 11 in the file 10, the file is apertured for the passage of the knob 13 of the ball member therethrough as indicated at 14, and to hold the ball member 11 in adjusted position in the file I utilize a plurality of spurs 15 (see Fig. 2). For two purposes, first; to facilitate depression of the exterior flange 16 of the ball member into the cover 10 and thereby avoid projection thereof above the

outer surface of the cover, and, second; in aid of the prevention of movement of such ball member on the cover, I form at the edge of the flange 16 an upturned rim 17. For 5 retaining the ball and socket members in position and thereby holding sheets of paper which have been properly apertured and inserted around the ball proper or knob 13. I provide on the socket member 12 a plurality 10 of fingers 18 inwardly turned as indicated at 19 and adapted to engage the shoulder 20 formed on the ball, thereby firmly gripping the inserted sheets between the inner surface 21 of the flange 22 and the inner surface 15 23 of the file. The flange 22 is formed with a downwardly turned rim 24 preferably positioned opposite the upwardly turned rim 17 on the ball member in order to compress the loose sheets therebetween 20 and overcome tendency of the sheets toward longitudinal movement relatively to the cover.

Referring now more particularly to Fig. 3, it will be seen that in the embodiment of 25 my invention here shown, the file cover 10^a is apertured for the reception of a socket member 12^a constructed similarly to that of Fig. 1, the fingers 18^a projecting from the surface 21^a being clearly shown in the plan 30 view of Fig. 4. The socket device 12^a is here held in position in the file cover by means of a washer 15^a, and the ball device 11^a formed similarly to that of Figs. 1 and 2 has a basal flange formed integrally therewith 35 with which is attached to the inner side of the cover by means of projections 15 adapted to pass through and engage the outer side of the cover just as in the device of Fig. 1 the projections 15 pass through and 40 engage the inner side of the cover. The ball device 11^a may alternatively be formed with a split knob comprising oppositely disposed members 25, 25, as shown in Fig. 5, which latter construction aids somewhat in the im- 45 placement of the socket upon the ball.

Referring now more particularly to Figs. 6 and 7, it will be observed that I have here illustrated a combined ball and socket lengthening and retaining device 26 adapted 50 to be inserted (in the position shown) between the members 11^a and 12^a of Fig. 3, or (by reversing) between the members 11 and 12 of Fig. 1, the said device comprising a unitary ball 11^b, socket 12^b and retaining 55 flange 21^b provided with a downward turned rim 17^b.

As will be understood on viewing Fig. 8, in cases where the use of a single device 60 26 does not give the requisite space between the members 11, 12, or 11^a—12^a, and where devices provided with the retaining flanges 21^b are not required, one or more members 27 coöperating with the members 11—12, 11^a—12^a may be used either alone or in con- 65 junction with one or more of the members

26, the member 27 being similar to the member 26 save in the omission of the flange.

In Figs. 9 and 10 I have illustrated the details of a pair of coöperating ball and socket devices 11^d and 12^d, useful for files 70 containing a considerable volume of sheets, the ball device 11^d being similar to that shown at 11 and 11^a save that between the split knob portions 25^d and flange 16^d is interposed an extended shank 28, and the 75 socket device 12^d being similar to that shown in Fig. 3 except that spurs 15^d are employed in lieu of the washer 15^a.

Referring now more particularly to Figs. 11, 12 and 13, it will be observable that I 80 have here shown my improved loose sheet holder as applied to a so-called "paper clip", wherein one or more ball members 11^e with corresponding socket members 12^e are mounted or preferably formed on a common 85 base 30, the device of Fig. 11 which carries but a single pair of the interlocking devices being more available in some cases in that it is less expensive than that of Fig. 12, which, however, is useful in other cases, 90 since it tends to restrain lateral separation of the sheets owing to the plurality of pairs of coöperating devices carried thereby.

As will be apparent upon inspection of Fig. 14, I have here shown a device combining the principal features of the devices of the preceding figures, a file cover 10^f being provided with a base 30^a carrying ball and socket members 11^f and 12^f, two of the combined lengthening and retaining members 26 100 and one of the members 27 being interposed therebetween. Upon examination of this figure it will be easily ascertained that sheets held in any one of the spaces 31, 32 or 33 can readily be removed without disturbance 105 of the sheets contained in any others of such spaces.

It is thought that my invention and the construction and operation of the devices embodying it will, in view of the foregoing 110 description, be fully comprehended without further or more amplified explanation.

Having thus described my invention and illustrated its use, what I claim as new and desire to secure by Letters Patent is:

1. In a device of the character described, in combination with a loose sheet holder, coöperating stemless ball and socket members adapted to be moved freely in all directions relatively to each other and disposed within the holder, and means for connecting them to the holder.

2. A device of the character described comprising, in combination, a loose sheet holder connected at its inner side to interiorly disposed detachable coöperating interlocking devices adapted to engage sheets between portions of such interlocking devices.

3. A device of the character described

- comprising, in combination, a continuous base connected at its inner side to coöperating flanged ball and socket members adapted to engage sheets between the flanges thereof.
- 5 4. In a device of the character described, in combination with a loose sheet holder provided with coöperating engaging members adapted to retain sheets between portions of the holder, a lengthening member 10 adapted for interposition between and spring engagement with said coöperating members, whereby intermediate sheets carried by the holder may be inserted or removed without disturbance of other sheets 15 carried therein.
5. In a device of the character described, in combination with a loose sheet holder provided with coöperating engaging members adapted to retain sheets between portions of the holder, a flanged retaining member adapted for interposition between and spring engagement with said coöperating members, whereby intermediate sheets carried by the holder may be inserted or removed without disturbance of other sheets 20 carried therein.
- 25 6. In a device of the character described, in combination with a loose sheet holder provided with coöperating engaging members adapted to retain sheets between portions of the holder, a flanged lengthening and retaining member adapted for interposition between and spring engagement with said coöperating members, whereby intermediate sheets carried by the holder may be inserted or removed without disturbance of other sheets 30 carried therein.
- 35 7. In a device of the character described, in combination with a loose sheet holder provided with coöperating engaging members adapted to retain sheets between portions of the holder, a lengthening member and a flanged retaining member adapted for spring engagement with each other and with said coöperating members, whereby intermediate sheets carried by the holder may be inserted or removed without disturbance of other sheets 40 carried therein.
- 45 8. In combination with a file cover, a loose sheet holder therein comprising coöperating ball and socket members adapted to retain sheets between portions of the holder, and a
- third ball and socket member having yieldingly resistant engagement with said first mentioned members for increasing the space 55 therebetween.
9. In combination with a file cover, a loose sheet holder therein comprising coöperating ball and socket members adapted to retain sheets between portions of the holder, and a third ball and socket member coöperating with said first mentioned members and flanged for retaining sheets on one thereof.
10. In combination with a file cover, a loose sheet holder therein comprising coöperating ball and socket members adapted to retain sheets between portions of the holder, and a third ball and socket member coöperating with said first mentioned members for increasing the space therebetween 60 and flanged for retaining sheets on one thereof.
11. A device of the character described comprising, in combination with a unitary folded base provided with a plurality of pairs of coöperating engaging devices adapted to hold sheets between the folded surfaces, whereby the sheets are restrained from lateral movement relatively to each other, intermediate flanged members each provided with yieldingly resistant means for engagement with said first mentioned devices whereby the distance between such devices may be increased.
12. A device of the character described comprising, in combination with a folded base provided with a plurality of pairs of coöperating ball and socket members adapted to hold sheets between the folded surfaces, intermediate members each provided with a ball and a socket portion coöperating with said first mentioned members, whereby the distance therebetween may be increased, said intermediate members having yieldingly resistant engagement.

In testimony whereof I have hereunto signed my name in the presence of the two subscribed witnesses.

JOSEPH EIFEL.
